INKING MECHANISM

Albert F. Pityo, Clifton, N. J., assignor to Tri
State Cap & Cap Machinery Co., Inc., Newark,
N. J., a corporation of New Jersey

Application December 4, 1935, Serial No. 52,746

16 Claims. (Cl. 101—340)

This invention relates to mechanism for inking reciprocating printing forms and more particularly to mechanism for inking inverted reciprocating printing forms. The invention relates to improvements over certain inking mechanism of this class containing spring means for bringing the form inking rollers into operation and which has certain defects, which tend to cause uncertain and abrupt action of the inking rollers 5 against the form, causing uneven distribution of ink and resulting in defective printing.

Moreover, the inking of inverted printing forms is more difficult and uncertain than for those not inverted and my invention embodies improved 15 means for overcoming the inherent difficulties of inking such forms and for producing a high speed mechanism of this type of greatly improved construction.

The principal object of the invention is to provide 20 a mechanism for inking an inverted reciprocating printing form which embodies an improved carriage for holding the form inking rollers, and which carriage is supplied with ink from a source at one side of the machine and 25 without the paths of operation of the form and its inking roller or rollers.

Another object is to provide positive means for guiding the form inking rollers and to eliminate the faulty action of spring mechanisms 30 which have been used in certain types of inking mechanism.

A further object is to provide a carriage for the form inking rollers which includes a pair of carriers which have a three point roller guiding or 35 cam contact system which controls the movements of the form inking roller or rollers.

Another object is to provide improvements in the supply roller system by providing more even and self adjusting means for holding the various 40 inking rollers in position and to impart suitable pressure to the same.

The means I prefer to employ for accomplishing the foregoing objects, together with other advantageous features of my improved inking 45 mechanism, are illustrated in the drawings accompanying and forming part of this specification, and in which—

Fig. 1 is a vertical transverse section of a portion of a printing machine embodying my improvements.

Fig. 2 is a front elevation of the same with certain parts in section.

Fig. 3 is a rear elevation of the same with certain parts in section.

Fig. 4 is a transverse vertical section of a por-

tion of the inking mechanism taken on the line 4—4 of Fig. 3.

Fig. 5 is a detail end elevation of part of the feed roller driving mechanism as seen from the left hand in Fig. 2.

Fig. 6 is a detail end elevation of the upper part of the machine as seen from the left in Fig. 3.

Fig. 7 is a plan of one end of one of the inking roller carriages and the carrier therefor.

Fig. 8 is a side elevation of one of the carriers for the form inking roller carriages.

Fig. 9 is a detail side elevation of the inner portion or branch of the same.

Fig. 10 is a plan of said portion.

Fig. 11 is a side elevation of the outer portion or branch of said carrier.

Fig. 12 is a plan of the same.

Fig. 13 is a detail side elevation of the cam for moving the oscillating rollers.

Referring to the drawings, the numeral 2 indicates the main machine bed and mounted thereon are two pedestals 3, one right hand and one left hand, and each having suitable guideways such as 5. Slidable in said guideways are the extensions 7 of the ram or printing bed 6, and immediately below the printing bed is the printing platen 8.

The printing bed or ram 6 is reciprocated by the pitmans 9 which extend downwardly through the main machine bed 2 and are moved up and down by eccentrics 10 one of which is illustrated in Fig. 1. Said eccentrics are mounted on the main drive shaft 11 which is located below the main machine bed. The pitmans 9 are connected with the ram 6 by means of the wrist pins 12.

Rotatably mounted on the pedestals 3 are two rings 13 containing internally toothed gear portions 14 which are driven by two pinion gears 15 mounted on the shaft 16. The rings 13 have 40 roller bearings 17 and are provided with annular grooves 18 in which bear the three guide blocks 19, so that the rings are guided and rotate together about the end parts of the ram 6.

Inward of the rings 13 are mounted two oppositely disposed cam structures 20, one around each end of the ram 6. The cam structures 20 are each composed of two parts, an upper stationary part 21, and a lower movable part 22, mounted on and reciprocating with the ram 6.

There are two inking roller carriages 24 for inking the printing form F. Each of said carriages is movable in an encircling path around the form and between the two cam structures 20. Immediately adjacent to the cam structures 20 55

at each end of the carriage is a movable carrier 25 forming part of the carriage 24. Each carrier is composed of an outer portion or branch 26, an inner portion or branch 27, and a bolt 28 to secure them together, said bolt being secured by the nut lock 29. Each of the outer portions has a slot 30 into which is fitted the tongue 31 of the inner portion or branch 27. A bore 33 is formed in the joint thus made in which an outer bushing 34 and an inner bushing 35 are placed and a bolt 36 is then put through the bushing 35, securing the carrier to the ring 13, there being a nut 37 on the farther side of the ring which secures the bolt thereon. Each of the carriers has an anti-friction roller 39 on its respective inner portion or branch and adapted to operate in the cam groove 40 of the adjacent cam structure 20.

Each pair of carriers 25 is connected together by suitable means such as the frame structure 20 42, said structure preferably including a bar 43 and two transverse members 44 one at each end of said bar. Two bearings 45 are provided in each of the members 44, in which are journaled the shafts 46 of the form inking rollers 47.

25 Mounted on the shafts 46 are the anti-friction rollers 49, one at each end of the inking roller 47 and adapted to roll on the cam surface 50 of the adjacent cam structure 20. The rollers 49 are hereinafter referred to as the outer cam contacts or cam contact elements and the rollers 36, as the inner cam contacts or cam contact elements.

Referring to Fig. 4 it will be noted that each set of cam contacts or rollers contains three cam contacts and the contacts are arranged in a triangular relation to each other and their axes are normally in fixed relation to one another. This triangular cam contact construction rotates around in the adjacent cam structure and around the end parts of the ram 6. The contours of the cam paths 40 and 50 of the cam structures 20 are such that the carriers are positively held during their rotation, in the proper path to cause the form inking rollers 47 to alternately take ink 45 from the supply roller 52 and deposit it on the printing form or plate F.

The form inking rollers 47 are readily removable from the carriage by reason of the carrier construction wherein each of the portions or branches 26 is provided with a hook shaped bearing 53 in which the pivots 54 of the frame structure 42 normally rest and are secured therein by latches 55 each having a notch 56 and whose free or operating ends are normally moved outwardly by springs 57.

60 The cam structures 20 are arranged so that the fixed and movable parts are always in operative connection, and to effect the connection of said parts, the adjacent portions are telescopically arranged, the fixed parts having slots 58 and the movable parts having tongues 59, the said tongues always bearing in said slots so that the cam paths or grooves 40 and the surfaces 50 are in effect continuous at all times and the cam contacts pass 65 smoothly from one part to the other without abrupt action.

At the upper part of the machine is located the large ink-supply roller 52 of greater diameter than that of the remainder of the ink rollers, and 70 its purpose is to supply ink to the carriages 24. There are two oscillating ink rollers 61 and 62 located near the ink fount 63, which is without the path of the carriages 24 and has the usual 75 ink supply roller 65 which operates intermittently

by mechanism not shown but which is well known in the art.

There is a carrying roller 66 which is moved to and fro between the fount roller 65 and the lower oscillating roller 62 by means of the arms 68 on the shaft 69, the latter being moved by the crank 70, connection rod 71, and bell crank 72 having the anti-friction roller 73 moved by the cam 74 on the main shaft 11.

There is an ink roller 75 which carries the ink 10 from the lower oscillating roller 62 to the upper oscillating roller 61. There is also an ink roller 76 which carries the ink from the upper oscillating roller 61 to the large supply roller 52. The bearing portions of the rollers 75 and 76 are journaled in yokes 78, one at each end, and said yokes are pivotally mounted on the pressure levers 79 by pivots 80, said levers being pivoted about the shaft 81 of the oscillating roller and are connected together by the bars 82 and 82c. The bar 82 is 20 normally pressed outwardly by the spring 83 coiled around the rod 84 between the collars 85, so that pressure is brought to bear on the ink rollers 75 and 76 by means of the levers 79 and yokes 78. The levers 79 are held from side motion by means of the bolts 79a in the lever slots 79b.

Driving of the various ink rollers above described is effected from the shaft 86 of the roller 52, which shaft is rotated by the sprocket 87, chain 88, and a suitable sprocket (not shown) on the main shaft 11. At the other end of the shaft 86 is a spur gear 89 which drives the wide pinion 90, which in turn drives the gear 91 on the shaft 92 of the oscillating roller 61. The gear 91 drives the wide pinion 93 which in turn drives the gear 94 on the shaft 81 of the lower oscillating roller 62. On the shaft 86 is a sprocket 95 which by means of the chain 96 drives the sprocket 97 journaled on the stud 98 together with the cam 99, which by means of the anti-friction roller 100 operates the double forked lever 101 on the shaft 102 in the lugs 3a' on the left hand pedestal 3. Collars 103 are secured to the shafts 81 and 92 of the oscillating rollers 62 and 61 and said collars have grooves 104 in which pins 105 on the lever 100 project so as to move the said shafts 81 and 92 together with the rollers 62 and 61 to and fro.

There is a gear 108 on the shaft 86 which meshes with the gear 109 on the shaft 16 which rotates the rings 13 by means of the pinions 15.

The lower parts 22 of the cam structures 20 are preferably made separate from the casting of the ram 6, and lugs 110 are provided on the parts 22 through which are passed the bolts 111 to secure the said parts to the extensions 112 on the ram 6.

There is a segmental ink distributing member 114 located between the fixed cam parts 21 and secured to the same by bolts 115 passed through the flanges 116 of said parts 21. Bolts 117 passed through bolt holes 118 in the pedestals 3, secure the stationary cam parts 21, together with the member 114, to said pedestals. There is a socket 114a in the member 114 in which the inner end 85 of the rod 84 is seated.

The form inking rollers 47 and the ink rollers 75 and 76 are preferably covered with yielding material such as soft rubber which in the exterior views of said rollers in the drawings is 70 shown by stippling for the sake of clearness.

There are safety pins 120, one on each of the carrier portions 21, which function if the anti-friction rollers 39 become detached by breaking of their pins 39a or for other cause. Thus the 75

carriers will not move but a slight amount from their normal paths and the carriage will not collide with any parts in case of accident to the rollers 39.

5 The general operation of the machine is as follows;

Rotation of the main shaft 11 rotates the eccentrics 10, which in turn move the pitmans 9 up and down causing the ram or form bed 6 to 10 reciprocate. The chain 88 driven by the sprocket on the shaft 11 causes the sprocket 87 to rotate the shaft 86 and roller 52, the gear 89 rotates the gears 90, 91, 93 and 94, and by means of said gears the rollers 61, 76, 62 and 75 are rotated. 15 The cam 74, bell crank 72, connection rod 71, shaft 69 and arms 68 cause the roller 66 to move back and forth between the ink fount 63 and roller 62, supplying ink to the latter, which together with the roller 61 is oscillated by means 20 of the cam 99. The ink is carried from the roller 62 to the roller 75, thence to the roller 61, and from that to the roller 76, which transfers it to the carriage supply roller 52.

The carriages 24 are moved around the ram 6 and form F by means of the rings 13 driven by the pinions 15 on the shaft 16, which is rotated by means of the gears 108 and 109 on the shaft 86. The carriers 25 connect the remainder of the carriage to the rings 13 and the latter pull the carriages 24, which are guided positively by the anti-friction rollers 39 and 49, so that the form inking rollers 47 gather ink from the supply roller 52, carry it to the segmental distributing member 114 and further distribute it thereon, and thence 30 carry it to the form F, being positively guided over said form by means of the cam paths 40 and 50 adjacent thereto. This distribution of ink onto the form is uniform and the uneven action of spring pressed rollers is entirely eliminated by 35 the foregoing carriage construction.

What I claim is:—

1. An inking mechanism for a reciprocating printing form embodying a carriage movable around said form and including a carrier on the carriage, a form inking roller thereon connected with the carrier, and two part cam structure engaged by said carrier for controlling the carriage and roller movement, one part of said cam structure movable with the printing form.

50 2. An inking mechanism for a reciprocating printing form embodying a carriage movable around said form and including two carriers one at each end, a frame connecting and pivoted in said carriers, a form inking roller on said frame, and cam structure engaged by said carriers for controlling the carriage and inking roller movement.

3. An inking mechanism for a reciprocating printing form embodying a carriage movable around said form and including two carriers one at each end, means to connect the carriers, a form inking roller on the carriage, and two encircling cam structures one for each carrier for controlling the movement thereof, each cam structure including two parts in connection with each other one of said parts movable with the printing form.

4. An inking mechanism for a reciprocating printing form embodying a carriage movable around said form and including two carriers one at each end, each carrier having an inner portion and an outer portion, two driving members one at each end, means whereby the pairs of inner and outer carrier portions are connected to each other and pivoted to the adjacent driving member, a form inking roller on the carriage and

movable therewith, and cam structure engaged by the carrier cam contact elements for controlling the carriage and inking roller movement.

5. An inking mechanism for a reciprocating printing form embodying a carrier driving member, a carriage movable around said form and including a carrier having an inner portion, an outer portion, a cam contact element at the rear of each of said portions, means whereby they are connected to each other and pivoted to the carrier driving member at their forward ends, a form inking roller on and movable with said carriage, and cam structure engaged by the carrier cam contact elements for controlling the carrier movement.

15 6. An inking mechanism for a reciprocating printing form embodying a carriage movable around said form and including a carrier having an inner portion, an outer portion, connecting means for said portions, driving means for the carrier, said portions connected to the driving means at one end, a cam contact element for said outer portion, and a cam contact element for said inner portion, a form inking roller mounted on said carriage, and cam structure engaged by 25 said cam contact elements for controlling the carrier movement.

7. An inking mechanism for a reciprocating printing form embodying a carriage movable around said form and including two carriers one 30 at each end, means to connect the carriers, a form inking roller on said means, and two encircling cam structures one for each carrier for controlling its movement, each cam structure including two parts which are telescopic with 35 relation to each other, one of said parts movable with the printing form.

8. An inking mechanism for a reciprocating printing form embodying a carriage movable around said form and including two carriers one 40 at each end, means to connect the carriers, an outer cam contact for each carrier, an inner cam contact for each carrier, a form inking roller on the carriage, and two encircling cam structures one for each carrier for controlling its movement 45 and having two cam paths, one to engage the outer cam contact and one to engage the inner cam contact, said cam structures each including a stationary part and a movable part.

9. An inking mechanism for a reciprocating 50 printing form embodying a carriage movable around said form and including two carriers one at each end, each carrier having an inner portion and an outer portion locked at one end, carrier driving means, each carrier connected to its driving means at the locked end, structure to connect the carriers, a form inking roller mounted on said structure, and two encircling cam structures one for each carrier for controlling the movement thereof.

10. An inking mechanism for a reciprocating printing form embodying a carriage movable around said form and including two carriers one at each end, frame structure to connect the carriers, a form inking roller mounted on said structure, and two encircling cam structures one for each carrier for controlling its movement and each including a stationary part and a movable part.

11. An inking mechanism for a reciprocating 70 printing form embodying a carriage movable around said form and including two carriers movable with said carriage one at each end, frame structure to connect the carriers, a form inking roller mounted on and rotatable on said structure,

and a cam structure for each carrier and engaged thereby for controlling its movement, each cam structure including a stationary part and a movable part.

5 12. In an inking mechanism, a carriage supply roller, two oscillating rollers in spaced relation to the supply roller, a feed roller joining the supply roller to the nearer oscillating roller, a feed roller joining the two oscillating rollers, two yokes each 10 adjacent the ends of the two feed rollers and adapted to journal the same, and means to press said yokes toward the oscillating rollers and supply roller.

13. In an inking mechanism, a carriage supply 15 roller, two oscillating rollers in spaced relation to the supply roller, a feed roller joining the supply roller to the nearer oscillating roller, a feed roller joining the two oscillating rollers, two yokes each 20 adjacent the ends of the two feed rollers and adapted to journal the same, two pressure levers one for each yoke, and means to press the levers against said yokes.

14. An inking mechanism for a reciprocating 25 printing form embodying a carriage movable around said form and including two carriers, two outer cam contacts for each carrier, an inner cam contact for each carrier, structure connecting the carriers and a form inking roller on said structure, means to rotate the carriers around said form, and 30 two cam structures each substantially continuous, one for each carrier, each such structure having two parts one of which is movable with said form,

each of said structures having two cam paths, one for the outer cam contacts of its carrier and the other for the inner cam contact thereof and together effective to control the carrier movement.

15. An inking mechanism for a reciprocating 5 printing form comprising a carriage movable around said form and including two carriers one at each end, means to connect the carriers, a form inking roller on said means, two encircling 10 cam structures one for each carrier for controlling its movements each cam structure including two parts which are telescopic with relation to each other, one of said parts movable with the printing form, and means to supply ink to the form inking roller.

16. An inking mechanism for a reciprocating 15 printing form embodying a carriage movable around said form and including two carriers each carrier provided with an inner portion having a cam contact and an outer portion having a bearing at the rear end, structure connecting the carriers including two pivots one at each end carried respectively by said bearings and two transverse members respectively adjacent said pivots, a shaft journaled in said transverse members, a form 20 inking roller on said shaft, two cam rollers on said shaft one at each end, means to rotate the carriers around said form, and two cam structures each having two cam paths one for one of the first-mentioned cam contacts and the other for 25 one of said cam rollers.

ALBERT F. PITYO.
